UNITED STATES PATENT OFFICE.

ADELMER M. BATES, OF CHICAGO, ILLINOIS, ASSIGNOR TO BATES VALVE BAG COMPANY, OF CHICAGO, ILLINOIS, A CORPORATION OF WEST VIRGINIA.

TRANSPORTATION SYSTEM.

1,173,245.

Specification of Letters Patent.

Patented Feb. 29, 1916.

Application filed October 30, 1914. Serial No. 869,471.

To all whom it may concern:

Be it known that I, ADELMER M. BATES, a citizen of the United States, residing at Chicago, in the county of Cook and State 5 of Illinois, have invented a certain new and useful Improvement in Transportation Systems, of which the following is a specification.

My invention relates to a transportation 10 system intended for use particularly in factories, on docks and the like. In one form it is illustrated in the accompanying drawings, wherein—

Figure 1 is a side elevation; Fig. 2 a cross 15 section on the line 2—2 of Fig. 1; Fig. 3 a detail plan view partly in section; Fig. 4 a front elevation of a truck; Fig. 5 is a dia- grammatic lay-out plan.

Like parts are indicated by the same letter 20 in all the figures.

A is an overhead rail, B, B brackets on which it is supported, C, C hangers looped above at C¹ and each provide with a pulley or traveler C² running on the rail A. The 25 hanger is provided with a shelf or platform C³ below and is adapted to receive upon such platform the spools D provided each with the ends D¹, D² lying on opposite sides of the body of the hanger. The bottom of 30 the hanger is provided with an eye E to which may be secured a short length of chain E¹ at the lower end of which is attached the coupler E², which may be a rope, cable, chain or rod. At the lower end the 35 coupler has a hook E³. The spools are attached to the cable F and are adapted to be received into pockets F¹, F² in the periphery of the drive wheel F² which is supported on the shaft F³ and driven in any desired 40 manner.

G is a two-wheeled truck in this case shown with the handles G¹ and the wheels G² and a transverse twisted cable G³ between the two handles at the middle of which is 45 the loop G⁴ to receive the hook E³.

J is a factory floor preferably adapted to receive and permit the movement of trucks or vehicles therealong.

J¹, J² are filling spouts to which material 50 is supplied.

J³, J⁴ are freight cars on the track J⁵ at the side of the factory floor.

J⁶, J⁷ are the car doors opposite the factory doors.

J⁸ I have shown a single coupler and hanger,

but, of course, there may be any desired number of them attached at intervals along the line of the power pull. I have shown in Fig. 5 an arrangement of parts whereby the operators and the disengaged trucks 60 are at one side of the line of travel so as not to interfere with the moving trucks. This, of course, involves such a hanger and coupler as will be capable of lateral oscillation. I have shown the coupler as inclined 65 or trailing when engaged in drawing and supporting the free end of the truck. These parts could no doubt be greatly modified.

While the structure which I have shown is in point of fact a substantially correct 70 illustration of a working system, nevertheless I desire to have my drawings taken as in a sense diagrammatic or merely illustrative of a general type or form of apparatus which contains my invention, and I do not 75 wish to be limited to the particular form, structure, size, arrangement or proportion of the several parts.

The use and operation of my invention may be explained by referring to the particular form of structure here illustrated. Assuming, for example, the problem of filling freight cars arranged along the side of a cement mill, the bags of cement having 80 been filled by means of a valve filling process, the operation of a system embodying my invention will be as follows: The filling apparatuses are supposed to be in operation at some part of the factory and they supply material at one side of the transportation system and there the operators are placed and the bags are filled. Now these bags as soon as filled are to be transported to some other part of the factory, as for example, to the doors where the freight cars 85 are lined up. The operators will be stationed one or more at the filling or filled bag receiving station at one side of the line of travel of the trucks and one or more at the point where the bagged material is to 90 be put into the cars. The bag loaders will have each an empty truck and they will load or supply the truck with the filled bags as illustrated in the drawing, and when a truck has been so loaded, the operator will 95 seize the next coupler and hook it into the loop or eye between the handles of the truck. The continuously moving power pull will, of course, immediately tighten the 100 coupler, as soon as the operator releases the 105

handles thus throwing the weight of the free end onto the coupler and hanger and wheel which supports the same, this secures the hook in the loop, and draws the truck toward the line of travel and then forwardly with or in the line of travel. Such loaded truck will proceed on its way rolling upon its two floor wheels and supported at a slight forward inclination from the hanger and its wheel until it has reached the point where the material is to be unloaded. The operator there stationed will seize the truck handles and lift them slightly, whereupon the hook will disengage, because the coupler being in a trailing or inclined position will, as soon as the pressure is taken off its lower end by the disengagement of the hook from the loop, fall into a vertical position, thus freeing the truck. The operator will now move the truck into the desired position, as for example to or into the car, and dump the contents or unload it. He will then bring out the empty truck at one side of the line of travel, seize the next empty or disengaged coupler, draw it to one side of the line of travel, hook it into the loop of the truck and as an empty the truck will proceed as before drawn by the power pull until it reaches the place where some operator desires an empty truck.

Of course, there may be any desired number of operators, any desired number of places where the empty trucks are filled and attached, and any desired number of places where the filled trucks are disengaged, emptied and reattached to the power pull. The power pull may have any desired circuit of travel and proceed upon different elevations. It is substantially overhead and out of the way and when not supplied with trucks or vehicles continues its course, carrying the series of couplers in an endless procession along the line of travel.

By having the couplers so that they can be easily moved or easily swung laterally from the line of travel, it is possible for all the operations to be carried on without interference, and there may be a quick progression of the filled or empty trucks or both passing each point of operation without interference with the operators.

Obviously the trucks may be of any desired character and I have used the term vehicle as a broader term than the one suggested by the device used in the illustrations. I mean by vehicle to indicate any transportation device traveling when in my system on a pivotal support and adapted to travel or be moved over or upon the track or floor surface upon which it rests. All that is necessary is a proper supporting surface and the floor of the factory dock or the like would be usually all that is necessary. The power pull moves continuously

in the same direction and is preferably driven by a drive wheel which engages the supports or other like devices on the cable. The hangers may be of any desired character, but something like what is here illustrated is likely to be found to be the best. There would normally be one hanger for each third or fourth spool and the hanger and associated spool are so shaped and arranged that they permit the proper action of the driving wheel, the spool being received into the pockets thereof. I have shown a very simple hanger and means of attachment to the truck, but other forms of device could be made. In the preferred form of my device there is an overhead continuously moving power pull, a series of hangers depending therefrom and carried thereby, a series of couplers preferably oscillatory so that they can be swung laterally from the line of travel and preferably longer than the interval between the pull and the part of the vehicle to which the coupler is attached so that they will tend to trail, a series of vehicles the weight of which rests upon the supporting surface and over which they are adapted to travel and an arrangement or means whereby a coupler can be engaged or disengaged with a truck or vehicle while the pull is in motion and the vehicle at rest or in motion as the case may be.

To effect the connection between the truck or vehicle and the power pull, I have shown a hanger connected to and traveling with the pull and a chain and coupler depending therefrom. Of course, the essential point is simply a coupler from the pull to the truck or vehicle and the term "coupler" as distinguished from the expression "coupler extension". I shall employ as indicating broadly the entire means for making the connection between the truck and the power pull. The disengaging point I have shown as at the truck, but, of course, it might be elsewhere. A short length of chain furnishes for practical purposes a universal joint or swivel forming part of the coupler.

I claim:

1. A transportation system comprising an overhead supported traveling power pull, a lower supporting surface, a vehicle having at one end a pivotal traveling support on the surface and a detachable coupler from the unsupported end of the vehicle to the power pull whereby such end of the vehicle is supported and the vehicle is carried forward over the surface by the pull.

2. A transportation system comprising an overhead traveling support, a traveling power pull, a lower supporting surface, a vehicle having at one end a pivotal traveling support on the surface and a detachable coupler from the unsupported end of the vehicle to the overhead traveling support

and the power pull whereby such end of the vehicle is supported and the vehicle is carried forward over the surface by the pull.

3. A transportation system comprising an overhead rail with a traveler thereon, a traveling power pull, a lower supporting surface, a vehicle having at one end a pivotal traveling support on the surface and a detachable coupler from the unsupported 5 end of the vehicle to the traveler and the power pull whereby such end of the vehicle is supported and the vehicle is carried forward over the surface by the pull.

4. A transportation system comprising an overhead rail with a traveling pulley thereon, a power pull connected with and supported by such pulley, a lower supporting surface, a vehicle having at one end a pivotal traveling support on the surface, and a 15 detachable coupler from the unsupported end of the vehicle to the pulley and the power pull whereby such end of the vehicle is supported and the vehicle is carried forward over the surface by the pull.

25 5. A transportation system comprising an overhead supported traveling power pull, a lower supporting surface, a vehicle having at one end a pivotal traveling support on the surface and a detachable laterally swinging 30 coupler from the unsupported end of the vehicle to the power pull whereby such end of the vehicle is supported and the vehicle is carried forward over the surface by the pull.

6. A transportation system comprising an overhead traveling support, a traveling power pull, a lower supporting surface, a vehicle having at one end a pivotal travel- 35

ing support on the surface and a detachable laterally swinging coupler from the unsupported end of the vehicle to the overhead 40 traveling support and the power pull whereby such end of the vehicle is supported and the vehicle is carried forward over the surface by the pull.

7. A transportation system comprising an overhead rail with a traveler thereon, a traveling power pull, a lower supporting surface, a vehicle having at one end a pivotal traveling support on the surface and a detachable laterally swinging coupler from 45 the unsupported end of the vehicle to the traveler and the power pull whereby such end of the vehicle is supported and the vehicle is carried forward over the surface 50 by the pull.

8. A transportation system comprising an overhead rail with a traveling pulley thereon, a power pull connected with and supported by such pulley, a lower supporting surface, a vehicle having at one end a pivotal traveling support on the surface, and a 55 detachable laterally swinging coupler from the unsupported end of the vehicle to the pulley and the power pull whereby such end of the vehicle is supported and the vehicle 60 is carried forward over the surface by the pull.

In testimony whereof, I affix my signature in the presence of a witness this 22nd day of October, 1914.

ADELMER M. BATES.
